Attorney, Agent, or Firm—David Rabin

[21] Appl. No.: 734,951

[57] CLAIM

The ornamental design for a sofa, as shown and described.

[22] Filed: Oct. 22, 1976

DESCRIPTION

[51] Int. Cl. .... D6—01
[52] U.S. Cl. D6/62; D6/68
[58] Field of Search D6/37-39,
D6/47-78; 297/232, 233, 248

The FIGURE is a perspective view of a sofa showing my design.

The end of the sofa not shown is a mirror image of the end shown while the back is conventional in appearance.
